METHOD OF AND MEANS FOR PREVENTING RADIATION AND EXTRA RERADIATION IN
RADIORECEIVERS

Application filed June 17, 1924. Serial No. 720,708.

This invention relates to radio receivers and particularly to radio receivers employing regenerative or oscillatory audion elements.

Radio receivers employing regeneration are often used for the reception of both modulated and unmodulated radio frequency signals. In the former case the regeneration is used to amplify the signal; in the latter case the regeneration is pushed to the point of oscillation and the signal is rendered audible by the heterodyne beating of the local and signal oscillations. The latter action is employed also in the so-called superheterodyne method of reception in which the signal frequency is lowered previous to amplification.

In the present practice the regenerative or oscillatory elements of the receiver affect the current in the antenna and cause either radiation or extra reradiation. Radiation is caused when the local generation of energy is quite independent of the incoming signal. An example of this is a regenerative receiver which is allowed to oscillate. Extra reradiation is due to the regenerative effect in the antenna, and is distinguished from normal reradiation. The normal reradiation is the natural reflection from the antenna system, no regeneration being present. It is equal to the square of the antenna current multiplied by the reradiation resistance. When regeneration is present the antenna current is increased or decreased from its normal value and the reradiation is changed from its normal amount; the difference is called the extra reradiation in this discussion.

While all reradiation affects another neighboring antenna structure and receiver and may become undesirable, yet the normal reradiation cannot very well be eliminated unless perhaps by a specially frequency-independent regenerative increase of antenna resistance or by actually altering the geometry of the antenna. Both the radiation and the extra reradiation may be eliminated, however, by the method of this invention. Such an object is very desirable, since radiation can interfere with the proper reception of signals at other nearby stations. With the present-day congestion of radio receivers, radiating receivers are a very general nuisance, especially in connection with radio telephone reception.

As the regeneration can be forced to the point of oscillation, both the regenerative and the oscillatory elements of receiving sets can be defined as "elements capable of sustained self-oscillation" but for convenience of description the simpler expression "oscillatory element" will be used in the following specification and claims in reference to regenerative as well as true oscillatory elements such as are purposely employed in heterodyne reception.

An object of the invention is to provide a radio receiver in which the amplification of the current or generation of other currents in the antenna or other collecting device by an oscillatory element is eliminated. An object is to provide a radio receiver including an oscillatory element, but which will not cause undesirable extra reradiation. A further object of the invention is to provide a radio receiver in which a substantially perfectly one-way repeater element is located between the current collecting means and an oscillatory element. More specifically an object of the invention is to provide a substantially perfectly one-way audion repeater.

These and other objects of the invention will be apparent from the following specification when considered in connection with the accompanying drawings, in which

Fig. 1 is a diagram showing the schematic organization of the invention;

Fig. 2 is a circuit diagram showing an audion repeater element with arrangements for rendering it unidirectional, the effects of capacity coupling being eliminated by a compensation method;

Fig. 3 is a circuit diagram of a modification of the circuit of Fig. 2;

Fig. 4 is a circuit diagram showing an audion repeater element with arrangements for rendering it unidirectional, the effects of a capacity coupling being eliminated by an alternative compensation method;

Fig. 5 is a circuit diagram showing an audion repeater element with arrangements for rendering it unidirectional, the effects of

capacity coupling being eliminated by a neutralization method;

Fig. 6 is a circuit diagram showing an audion repeater element with arrangements for rendering it unidirectional, the effects of capacity coupling being eliminated by a modified Hazeltine neutralization method.

Fig. 7 is a circuit diagram showing the relation of the unidirectional repeater element of the type of Fig. 2 to an antenna and regenerative receiver of conventional type.

Fig. 8 is a circuit diagram showing the unidirectional repeater element of the type of Fig. 2 used with a coil antenna and superheterodyne receiver of conventional type.

I shall now proceed to describe my invention with reference to a number of specific embodiments, giving, for the sake of a clear disclosure, definite constants and relations. I wish it to be distinctly understood, however, that my invention is in no way limited to the specific embodiments herein recited or to circuit constants or other values here given.

The fundamental organization of the invention is shown schematically in Fig. 1. The antenna is brought to resonance with the signal to be received by means of the antenna tuning apparatus 1. The tuning network is designed to furnish to the input terminals of the unidirectional repeater 2 a high voltage and small current. This is amplified by the repeater and passed on, through suitable coupling impedances, to the receiving apparatus 3. The receiver contains oscillatory elements which will in general cause large currents to flow in the plate circuit of the unidirectional repeater. For the success of the invention it is necessary that these currents be prevented from establishing any difference of potential across the input terminals, in other words, that the device be unidirectional. By the term unidirectional repeater or unidirectional audion stage as herein used, I mean a repeater or audion stage which while operating over a predetermined frequency range will transmit impressed oscillations in one direction, but will not to any appreciable extent transmit oscillations in the reverse direction. If this repeater is of the audion type and properly designed it not only attains the object of the invention but serves as a stage of amplification as well and is of two-fold utility. The audion repeater element is rendered perfectly unidirectional by providing special means for eliminating the effect of the current in the plate circuit upon the grid circuit, to which the antenna is connected. (In this discussion the term "antenna" is used generically to denote the collecting means, of whatever form.) An ordinary audion repeater will not do on account of several actions which will be explained presently. The most important of these is the capacity coupling engendered by the capacity between the grid and plate electrodes of the audion, and between the wires

and apparatus connected to these electrodes. The extra-audion capacity can be largely eliminated by shielding, as is well known to those skilled in the art; the effects of the intro-audion capacity may be eliminated by special methods described in my co-pending application, Ser. No. 629,702, filed April 3, 1923. In addition to this capacity coupling, other couplings exist whose effects and the means for eliminating them are hereinafter disclosed.

An audion repeater element of ordinary type will usually not be unidirectional for several reasons, as follows:

1. On account of the electrostatic coupling due to the capacity between grid and plate electrodes of the audion and their connections;

2. On account of the flow of ions or electrons from the filament to the grid of the audion;

3. On account of the coupling due to the flow of the plate (thermionic) current through the filament;

4. On account of the charge induced upon the grid electrode by the varying space charge;

5. On account of any incidental coupling between the coils or condensers and their connections on either side of the repeater tube.

The capacity coupling is compensated or neutralized by the general methods disclosed in my copending application or by the specific methods disclosed in the patent to Rice No. 1,384,118, or the patents to Hazeltine Nos. 1,450,080 and 1,489,228.

The coupling due to the effect of the varying plate voltage upon any thermionic current that may be flowing from filament to grid may be eliminated by biasing the grid and otherwise choosing the normal electrode voltages so that the smallest possible grid current flows in the range of grid voltage impressed upon the device. This is sometimes accomplished by connecting the grid return to the negative terminal of the filament; in other cases it may be necessary to insert a "C" battery.

The effect upon the grid circuit of the plate current through the filament arises from the finite resistance of the filament and is of importance only in the case of tubes having high resistance filaments. Examples of this are the audions known to the trade as Type UV-201A, which have filament resistances between terminals of the order of 20 ohms. If the plate return connects to one filament terminal the alternating plate current flowing through the filament will cause the potential of every other part of the filament, with respect to this terminal, to vary, with the result that a varying charge is induced upon the grid. I propose to minimize this effect by allowing the alternating constituent of the plate current to enter the filament at both ter-

minals. This may be accomplished by shunting the filament terminals by a large condenser, the impedance of this condenser to the currents to be amplified being very small compared with the resistance of the filament and of the "A" battery and its connections. A capacity of the order of one microfarad is indicated at a frequency of one million cycles (300 meter wave length).

10 The effect of the varying space charge upon the charge induced upon the grid electrode resembles that due to the grid-plate capacity of the audion. The latter capacity coupling is due to the induction upon the grid 15 of a charge by the varying plate charge. When the audion filament is not heated this is the only coupling of this kind which exists. When the tube is lighted, however, part of the electric flux from the plate is deflected to 20 the electrons or space charge with the result that the effective grid-plate capacity is changed. The general method of balancing, either by compensation or neutralization, described in my copending application may be 25 used to eliminate this effect. A resistance component may sometimes appear, in which case a perfect frequency-independent balance can be obtained only by adding extra resistance in the compensating or neutralizing network.

30 The incidental couplings, of electromagnetic, electrostatic or other types, between the apparatus and connecting wires external to the audion may be eliminated by judicious 35 shielding, as is well known to those skilled in the art. Since such shielding is general practice it cannot be considered part of this invention and is therefore omitted from the diagrams. The coupling between coils can 40 usually be eliminated by a proper geometric arrangement, or by surrounding the coils by a copper shield of sufficient thickness. The proper thickness will be determined by the extinction coefficient of the metal and the 45 frequency; for example, a thickness of 0.015" would be indicated for copper or silver at 300 meters.

50 These methods of rendering the repeater unit completely unidirectional are illustrated in Figs. 2, 3, 4, 5 and 6. The variety of these arrangements is due to the different methods of eliminating the effective capacity coupling.

55 Fig. 2 represents a repeater element suitable for interposition between an antenna and later oscillatory element. The method of compensating capacity coupling described in my copending application, Serial Number 629,702, and shown in Fig. 4 thereof, is used here. Figs. 2 and 3 differ in the 60 method of forming the compensating winding. The reference symbols are uniform so that the following description applies to both circuits. L_1 and L_2 constitute the input 65 transformer tuned by means of the variable

condenser C_2 . Any other suitable input arrangement may be made. The A, B and C batteries have their conventional locations. As described in the copending application just cited, capacity compensation is obtained 70 by bringing point "Y" to the potential of the point "X." Point "Y" is the lower terminal of the input circuit, that is, the terminal having the lower alternating current potential, or, in general, most closely approaching to the 75 alternating current potential of the filament. This might have been done by directly connecting "X" and "Y" but an insulating condenser would then have been necessary to keep the plate battery voltage off the grid. 80 For this and other reasons the inductive method shown is to be preferred, since it brings "Y" to the direct current potential of the filament electrode. The output transformer is formed by L_4 and L_5 which are 85 tuned by C_3 . In Fig. 2 the compensation is obtained by an extra winding L_6 ; in Fig. 3 part of the coil L_5 is used for the same purpose. This is an example of a case where 90 L_6 is incorporated with other coils used in the circuit for other purposes. Other modifications of this idea will be obvious to one skilled in the art. C_1 is the filament shunting condenser of low impedance, which serves 95 to introduce the alternating current plate current through both filament terminals. R is a resistance which may be used to control the filament current and incidentally serve in biasing the grid negatively. C_e represents 100 a compensating capacity, which may obviously reside between the electrodes of the audion or their connecting wires, or in an external condenser. In certain cases it is desirable to add compensating resistances R_1 and R_2 to either C_m or C_e or both, either in 105 series, as shown in Fig. 2, or in parallel, Fig. 3. The introduction of such resistance or other balancing elements is in accordance with the principles of my copending application. I include them in these diagrams 110 for generality; they may be omitted in certain cases.

115 Fig. 4 represents a repeater unit suitable for interposition between an antenna and later oscillatory element, specifically a regenerative element. A modification of the method of compensating the audion capacity coupling described by Rice in Patent No. 1,384,118 is used. This modification consists among other things in the provision in the plate circuit of an extra inductance, L_6 , whose function is to prevent the circuit from oscillating at a period determined mainly by the inductance and distributed capacity of 120 the coils L_1 , L_2 and the inductance and capacity of the plate circuit of the audion. Some such means for suppressing these parasitic oscillations is desirable for rendering the circuit operative. In one specific experimental 125 130

arrangement with $L_1, L_2 = 200$ mchs., oscillations were obtained in a range of plate circuit inductance extending from 60 mchs. to 250 mchs., the wave length limits of these oscillations being 145 and 228 meters, respectively. To prevent oscillations the load inductance of the transformer should be greater than 250 mchs., or, L_5 may be added to make up the deficiency. Other methods of suppressing these oscillations can be easily devised, for example, I may use a condenser shunted by a high impedance choke-coil, the choke-coil serving to pass the steady normal plate current around the condenser. Special design of the transformer L_3, L_4 will often accomplish the same result. Referring to the diagram in this specific example, L_1 and L_2 are two inductors or parts of the same inductor; C_2 is a variable condenser for tuning; C_e is a compensating condenser whose capacity is of the order of 10^{-5} microfarads; R_e is a compensating resistance of the order of 10^5 ohms; "A" is the filament battery; "B" the plate battery and "C" is the battery used to bias the grid negatively to prevent the flow of thermionic current to the grid electrode; C_1 is a filament shunting condenser of low impedance; L_3, L_4 is the output transformer. The functions of all these parts have already been explained. The particular values of these constants are merely illustrative, and my invention is of course not limited thereto.

Fig. 5 illustrates a repeater unit in which the audion capacity coupling is eliminated by a neutralization method. The principle of such methods is disclosed in my copending application. Referring to the figure, L_1 and L_2 constitute the input transformer which is tuned by the condenser C_2 ; C_e is a compensating condenser; L_3 and L_4 are either separate coils or parts of the same coil; L_5 and C_3 represent the output circuit; R_e is a compensating resistance; R is a resistance in the filament circuit, the direct current drop across which is used to give the grid a suitable negative bias; the "C" battery reinforces the biasing effect of R ; the "A" and "B" batteries have their conventional circuit locations; C_1 is a filament-shunting condenser of low impedance. The output circuit, represented by the coil L_5 must be coupled to L_3 and L_4 so that the effective impedances between the terminals of L_3 and L_4 are of proper value to maintain a state of balance in the circuit; obviously also the coupling between L_3, L_4 and L_5 must be fixed. It is not necessary that L_3 and L_4 be coupled together, but their couplings to L_5 must result in impedances between their terminals which satisfy the requirements of neutralization. For best results with tubes of the usual 15,000 ohms plate resistance the coils L_3 and L_4 are of small inductance compared with that of L_5 and the coupling be-

tween L_3 and L_5 and between L_4 and L_5 should be close. In order that persons skilled in the art may reproduce my results, I give the following constants of one specific circuit; $L_3 = 20$ microhenries; $L_4 = 20$ microhenries; $L_5 = 300$ microhenries; $C_3 = 0.00033$ microfarads; $C_e = 0.000005$ microfarads. These values were found suitable for a unit designed to cover a wave length range of 200 to 600 meters.

Fig. 6 illustrates a repeater unit in which an alternative method of neutralizing the audion capacity coupling is employed. The other arrangements for eliminating the enumerated couplings other than that due to the audion capacity are those already described. L_1 and L_2 are two coils of preferably tight couplings wound in opposite directions and so connected that their non-common terminal voltages are opposite in phase; C_e is a compensating condenser; R_1 and R_2 are compensating resistances, which make up the departure of the voltages of L_1 and L_2 from exact 180° phase relationship and which also compensate for the resistance component of the variable space charge coupling; R is a filament resistance, the drop across which helps to bias the grid negatively; the battery "C" also has this function; C_1 is a filament-shunting condenser of low impedance; the batteries "A" and "B" have their conventional functions; L_3 and L_4 constitute the output transformer, tuned by the condenser C_4 .

While my invention is not, of course, limited to any particular form of output circuit or transformer, a few observations on the design of the tuned output transformer will be included as the proper design of this element is desirable for the efficient operation of the repeater. Since the output will usually be into the grid circuit of another audion, the problem is that of obtaining a maximum secondary voltage in the coupled circuit arrangement. Let L_1, L_2 be the primary and secondary inductances respectively, and C_2 the secondary capacity. The coupling between L_1 and L_2 is preferably made unity, in which case the maximum voltage across the secondary will be obtained when the secondary condenser is tuned so that:

$$\omega L_2 - \frac{1}{\omega C_2} = - \frac{R_2 \omega L_1}{R_1} \quad (1)$$

L_2, L_1 and C_2 are under the control of the designer. L_2 and C_2 are essentially related by the resonance condition. Usually the amplifier unit will be required to operate over a band of wave lengths, in which case the inductance of L_2 is fixed when the maximum capacity of C_2 and the upper wave length limit is specified. L_2 is also governed to some extent by the variation of R_2 with L_2 for a particular coil construction. Once

L_2 has been decided upon the optimum L_1 can be calculated from the relation:

$$L_1(\text{opt.}) = C_2 R_1 R_2 \quad (2)$$

5 R_2 is the effective secondary resistance; R_1 is the primary resistance plus the internal plate resistance of the amplifier tube. It is important to note that in the use contemplated in this invention, where the repeater element may be succeeded by a regenerative 10 element, the secondary resistance R_2 will be diminished from its normal value by regeneration, so that Formula (2) shows immediately that L_1 should be made considerably lower than it would be in the case of a normal multistage amplifier. In many cases L_1 15 may be advantageously reduced to a single turn, or if tighter coupling is desired, a number of single turns in parallel.

20 These mathematical conclusions can be directly applied to the design of the output transformer in such arrangements as Figs. 2, 3 and 6; in applying them to the arrangement of Fig. 5, it must be noticed that none 25 of the load current is carried by the coil L_4 of Fig. 5. The optimum primary inductance is entirely contained in the coil L_3 of Fig. 5. With this understanding the principles apply uniformly.

30 Specific applications of the invention are shown in Figs. 7 and 8. Fig. 7 shows the detailed circuit diagram of a unidirectional repeater of the type of Fig. 2 connected in front of a regenerative receiver of conventional type. An antenna of ordinary elevated type is shown. The repeater unit is so designed that from the point of view of the regenerative receiver its output circuit has electrical resemblance to an antenna, so that the unit 35 can be placed in front of different receivers without special modification. Referring to Fig. 7, L_1 and L_2 represent the input transformer, which with the condenser C_2 serves to tune the antenna; C_3 is a compensating condenser, which may be partly external to the audion or be replaced completely by the grid-filament audion capacity; C_1 is a filament shunting condenser of low impedance, which with tubes having high filament resistances, 40 serves to reduce the effect of the thermionic return current upon the grid potential; L_3 is an inductance to which or to part of which the compensating coil L_4 is coupled; C_5 is a condenser whose capacity may be approximately that of an average antenna; "C" is a battery used to bias the grid of the repeater tube 1 negatively, and R_1 , R_2 are phase compensating resistances. In the regenerative receiver, L_5 and C_4 constitute the tuned grid 45 input circuit; regeneration is obtained by back-coupling through the tickler coil L_6 as described in Armstrong, U. S. Patent No. 1,113,149; 2 is the detector audion of the regenerative receiver, 3 and 4 being audio 50 amplifiers coupled through the audio trans-

formers T_1 and T_2 ; the remaining parts of the regenerative receiver are incidental and conventional and require no special comment. If the antenna were directly connected to L_5 as in present practice, the regenerative amplification would change the current in the antenna and cause extra reradiation, or it could oscillate into the antenna and cause radiation. Both these possibilities are eliminated by the circuit of Fig. 7, because by 70 the interposition of a perfectly unidirectional repeater, the action can be relayed from grid to plate, but not in the opposite direction. 75

I have already pointed out that the effective grid-plate capacity of the audion is changed from its true geometrical value by the flow of electrons; obviously, therefore, the repeater circuits must be balanced with the filament of the audio heated, with the normal filament current flowing and normal electrode voltages impressed. A cold-tube balance will be spurious. In the circuit used in Fig. 7 and Fig. 2, where the grid-filament capacity of the audion is in the balancing arm of the bridge, the same remarks apply to the grid-filament capacity. This too will be subject to change by the electronic current, and since its change will not in general exactly follow that of the grid-plate capacity, a hot-tube balance will be required. Since these effects are new I will give the following experimental data concerning them. The constants of one specific repeater circuit (Fig. 7) were as follows: $L_4=25$ microhenries, $C_2=0.00025$ microfarads, L_5 comprises 12 microhenries fitting over L_4 with air space and located near ground potential point of L_4 . Letting the regenerative receiver oscillate and listening on the antenna side with a two-stage amplifier, it is possible to get complete extinction by varying C_3 . The balance point varies with the frequency due to capacity unbalance between L_3 and L_4 and to variation of electronic component of inter-electrode capacities. The value of C_3 varies consistently with the filament temperature; when filament is lit to full brilliancy C_3 is from 5 to 9 microfarads less than for cold tube. 100

105 Fig. 8 shows a second embodiment. In this case a coil antenna is used, no input transformer being necessary, and the unilateral repeater is of the type of Fig. 4. A superheterodyne receiver of conventional type succeeds the repeater. This is an example of a true oscillatory element rather than a regenerative element, the object in this case being to prevent the oscillation generated by the local oscillator, O, from reaching the antenna. The coil antenna L_1 , L_2 is a coil of 110 preferably large dimensions. It is preferably grounded at the electrical mid-winding to improve the directional properties and fix the potential of the filament circuit and bat- 115

teries with respect to earth. The coil is tuned by means of the condenser C_2 . The other symbols of the figure are uniform with those of Fig. 4. The output transformer is tuned by means of the condenser C_3 . The details of the superheterodyne receiver are the usual ones. O is the local oscillator coupled to the grid circuit of the frequency-changing audion 2, through L_5 L_6 . 3 is the detector audion, situated between the frequency-changer and the audio frequency amplifier. The operation of this circuit is the same as that of the preceding one.

While a true unidirectional repeater can be obtained only by correcting for each of the disturbing causes noted above, it is apparent that the amount of feed-back due to the several causes will vary with different tubes and to a smaller extent with the circuit in which the tube is employed. In some cases, therefore, a substantially one-way repeater action can be obtained without correcting for a disturbing influence which is of a negligible value.

25 I claim:

1. In a radio receiver, the combination with a current collecting device and an oscillatory element, of a unidirectional repeater located between said current collecting device and said oscillatory element, said unidirectional repeater comprising the combination of an audion tube with means for reducing effects upon the input circuit terminals of variations in potential across the output circuit terminals due to the grid-plate capacity of said tube, means for reducing the flow of current from the grid to the filament, means for reducing the flow of alternating plate current through the filament, and means for reducing incidental coupling between elements in the input and output circuits of said tube.

2. A unidirectional audion repeater comprising, in combination, means for reducing the effects upon the input circuit terminals of variations in potential across the plate circuit load due to the grid-plate capacity of the audion tube and the effects of the charge induced upon the grid by varying space charge in the tube, means for reducing the effects of the flow of current from the grid to the filament, means for reducing the effects of the flow of plate current through the filament, and means for reducing the effects of incidental coupling between elements in the input and output circuits of the tube.

3. A vacuum tube amplifier stage having an impedance network arranged in the form of an alternating current Wheatstone bridge of which the input and output circuits of the stage form conjugate arms, and of which one balancing arm comprises capacity between grid and plate, and a second balancing arm comprises a reactance and a phase-

adjusting resistance between grid and filament of the vacuum tube.

4. An electrical amplifier comprising a vacuum tube, an input circuit, and an output circuit including an output transformer of output transformer, the impedances between plate and filament of said vacuum tube, one terminal of said input circuit being connected to the grid of said vacuum tube, and the other terminal of said input circuit being connected to a point in the secondary of said output transformer, the impedances between grid and plate and between grid and filament of said vacuum tube cooperating with said output transformer to provide the four-balancing arms of an alternating current Wheatstone bridge across which said input and output circuits are arranged as conjugate arms.

5. A unidirectional audion repeater comprising, in combination, means adapted to reduce effects upon the input circuit terminals of variations in potential across the output circuit terminals due to the grid-plate capacity of the audion tube, means adapted to reduce effects due to flow of current between grid and filament, means adapted to reduce flow of alternating plate current through the filament, and means adapted to reduce effects of incidental coupling between elements of the input and output circuits.

6. A unidirectional amplifier stage comprising a vacuum tube having a control grid, cathode and plate; circuit elements providing an input and an output circuit for said stage, means for tuning one of said circuits to resonance at a desired frequency, means preventing the varying potential of said output circuit from acting through the grid-plate coupling to establish variations of potential across said input circuit, means establishing a direct current potential between said control grid and cathode to prevent the flow of current between cathode and grid, means rendering the direct current potential between said control grid and cathode substantially independent of the flow of space current through said cathode, and means shielding the elements of said input and output circuits to reduce incidental couplings to and between the same.

In testimony whereof, I affix my signature.
STUART BALLANTINE.
